DISPENSER CIGARETTE CASE

Stephen Kassovic, La Salle, Ill.

Application November 16, 1948, Serial No. 60,296

3 Claims. (CL. 312—73)

1

This invention relates to cigarette dispensers particularly adapted for use in motor vehicles, and in particular includes a barrel or cylindrical-shaped container having a channel-shaped depending section within an opening in the lower forward corner of the depending section through which cigarettes may be withdrawn by hand.

The purpose of this invention is to provide a unique cigarette dispenser that may be mounted on or in the instrument board of a motor vehicle so that cigarettes may be withdrawn by the operator of the vehicle without taking his eyes from the road ahead.

In the usual cigarette package or dispenser it is difficult for the operator of a motor vehicle to withdraw a cigarette with one hand and almost impossible to withdraw a cigarette without looking at the case.

With this thought in mind this invention contemplates a cigarette dispenser having a cylindrical upper end with a depending channel-shaped section having an outlet opening in the forward end and having a cylinder with a longitudinally disposed slot in the wall thereof rotatably mounted in the cylindrical upper end.

The object of this invention is, therefore, to provide a unique cigarette dispenser that may be mounted in the instrument board of a motor vehicle which may readily be filled and from which cigarettes may be withdrawn without looking at the dispenser.

Another object of the invention is to provide a cigarette dispenser adapted to be mounted on the instrument board of a motor vehicle which may readily be refilled.

A further object of the invention is to provide a cigarette dispenser for an instrument board of a motor vehicle that has a unique and attractive appearance and that is of a simple, and economical construction.

With these and other objects in view, the invention consists of the new and useful combination, construction, and arrangement of parts as hereinafter more fully described, set forth in the claims appended hereto, and disclosed in the accompanying drawing forming part hereof, wherein:

Figure 1 is a view showing a front elevation of the dispenser with the device mounted on an instrument board and with part of the instrument board broken away;

Figure 2 is a longitudinal section through the dispenser taken on line 2—2 of Figure 1;

Figure 3 is a front elevational view showing the outer case with the inner cylinder removed;

2

Figure 4 is a view looking upward toward the under side of the dispenser;

Figure 5 is a cross section through the dispenser taken on line 5—5 of Figure 2 and

Figure 6 is a detail showing the inner cylinder of the dispenser looking upward toward the under side thereof showing the longitudinal opening therein.

Referring now to the drawing wherein like reference characters denote corresponding parts the cigarette dispenser of this invention includes an outer case 10 and an inner cylinder 11 with the inner cylinder provided with a head 12 having a knurled flange 13.

The case 10 is provided with a cylindrical-shaped upper section 14 and a relatively narrow depending channel-shaped section 15. The section 15 is formed with side walls 16 and 17, a base 18, a front 19 and a rear wall 20, and the forward edges of the side walls 16 and 17 are provided with recesses 21 and 22 through which an end of a cigarette, as indicated by the dotted lines 23, may extend as shown in Figure 2. The lower end of the front wall 19 stops at a point corresponding with the upper edges of the recess wherein the cigarette may be gripped by the thumb and forefinger and readily withdrawn without operating the other parts of the case. The upper surface of the cylindrical section of the case is provided with a bead forming a stop 24 which is positioned to engage the outer surface of the instrument board 25 to limit movement of the case into the instrument board. The front wall 19 of the case is provided with a recess 26 that is positioned to receive a lug 27 on the flange 13 of the cylinder 11, and with the lug aligned with the longitudinal opening 28 in the cylinder 11 the position of the cylinder may be located in the case so that the open side is in the bottom.

The parts of the device may be made of plastic, or any other suitable material and it may be made of any convenient size.

With the parts arranged in this manner, the dispenser may be inserted in an opening in the instrument board of a motor vehicle and with the stop 24 limiting the movement of the dispenser in the instrument board, the knurled flange 13 will be spaced from the instrument board so that it may be conveniently gripped by the thumb and forefinger to rotate the same. To refill the dispenser, the cylinder 11 may be turned over with opening 23 in the upper side and then withdrawn, and after the cigarettes have been placed therein, it may be returned to the case

and turned over until the lug 27 snaps into the recess 26.

It will be understood that modifications may be made in the design and arrangement of the parts without departing from the spirit of the invention.

What is claimed is:

1. A cigarette dispenser comprising a case having a cylindrical upper section and a depending channel-shaped lower section positioned to receive cigarettes from the cylindrical upper section, said depending section having side walls, a base, front and rear walls and having recesses in the lower forward ends of the side walls with the lower end of the front wall and forward end of the base terminating at the edges of said recesses, said front wall having a recess in the outer surface positioned on the center of the cylindrical upper section of the case, and an inner cylinder having a longitudinally disposed opening therein and having a head with a knurled flange thereon at one end, said head having a lug positioned to register with the recess in the front wall of the depending lower section with the longitudinal opening of the cylinder registering with the said depending lower section. 25

2. A cigarette dispenser comprising a cylindrical case having a cigarette receiving longitudinally disposed depending lower section, said casing having an open outer end and the outer end of said depending section being spaced from the outer end of the case, an inner cigarette containing cylinder having a longitudinally disposed slot

in the wall thereof positioned to register with the depending lower section of the case with the inner cylinder positioned in the case, said inner cylinder having gripping means on the outer end for rotating the cylinder, and means limiting the rotation of the said inner cylinder.

3. A cigarette dispenser comprising a cylindrical case having a cigarette receiving longitudinally disposed depending lower section, said casing having an open outer end and the outer end of said depending section being spaced from the outer end of the case, an inner cigarette containing cylinder having a longitudinally disposed slot in the wall thereof positioned to register with the depending lower section of the case with the inner cylinder positioned in the case, said inner cylinder having gripping means on the outer end for rotating the cylinder, means on the case limiting the rotation of the said inner cylinder, and means on the inner cylinder coacting with means on the case for limiting the rotation of the said inner cylinder in the case.
